Patented Aug. 27, 1963

196,122

GAME SPINNER

Herbert R. Wells and Mary M. Wells, both of 14509 Hayward, Whittier, Calif.

Filed Mar. 13, 1963, Ser. No. 73,962

Term of patent 14 years

(Cl. D34—5)

FIG. 1

FIG. 2

We claim:

The ornamental design for a game spinner, substantially as shown.
